UNITED STATES PATENT OFFICE.

EDWARD E. FOSTER, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-PRESSING MACHINE.

1,326,489.

Specification of Letters Patent. Patented Dec. 30, 1919.

Application filed July 1, 1916. Serial No. 107,154.

To all whom it may concern:

Be it known that I, EDWARD E. FOSTER, a citizen of the United States, residing at Beverly, in the county of Essex and State 5 of Massachusetts, have invented certain new and useful Improvements in Sole-Pressing Machines; and I do hereby declare the following to be a full, clear, and exact description of the invention, such as will enable 10 others skilled in the art to which it appertains to make and use the same.

This invention relates to sole pressing machines which are employed for laying and leveling shoe soles.

15 In the progressive pressure, sole pressing machine shown in the patent to Mayo, No. 1,146,341, dated July 18, 1915, a sole pressing pad is employed which is made up in sections. The sections of the pad are attached 20 to a rotary drum on which the pad is wound and from which it is unwound when removing and applying the pad to the sole of a shoe. This type of pad is expensive to manufacture and difficult to properly shape 25 for treating different kinds of shoes. Also, the junction between the sections has a tendency to make marks on the sole when a heavy pressure is applied to the pad. In applying the pad to the sole, the sections are 30 progressively brought into operative position, and this progressive movement often tends to displace the sole on the shoe.

The primary object of the present invention is to provide a progressive pressure, 35 sole pressing machine which will overcome the objectionable features mentioned above, and which will accurately and effectively lay and level the soles of shoes.

In accordance with this object, one feature of the invention contemplates the provision in a progressive pressure, sole pressing machine, of a continuous sole pressing form which may be initially applied to cover the entire surface of the sole simultaneously. 40 In the preferred form of the invention, the sole pressing form consists of a yieldable pad for laying soles which is mounted on a flexible carrier. The carrier is suspended between the machine frame and a pad applying frame, and the pad applying frame is oscillated in placing the pad upon and removing it from the sole of a shoe. The pad applying frame is actuated by a pres-

sure cradle which carries a series of rollers that move across a flange on the sides of the 55 carrier to apply pressure only outside of the edges of a sole.

Another object of the invention is to provide a driving mechanism for a sole pressing machine having two sets of forms and 60 jacks by which any desired pressing movement of the sets can be obtained.

With this object in view, another feature of the invention contemplates the provision in a sole pressing machine having two sets 65 of forms and jacks with a separate driving mechanism for each, of means for independently connecting each set with its driving mechanism, and means for simultaneously 70 connecting both sets with their driving mechanisms. With this construction, each set may be operated independently of the other, and the two sets may be operated together so as to move into pressure relation 75 either alternately or at the same time.

Other features of the invention consist in certain features of construction and combinations of parts which are hereinafter described and set forth in the claims.

The various features of the invention are 80 illustrated in the accompanying drawings, in which Figure 1 is a view in side elevation showing a progressive pressure, sole-laying machine embodying the preferred form of the invention; Fig. 2 is a view in 85 front elevation of the upper portion of the sole-laying machine showing the portion of the pressing form when removed from the shoe; Fig. 3 is a view in side elevation, partly in section, of the parts shown in Fig. 90 2; Fig. 4 is a view in side elevation, partly in section, showing the pressing form in pressure position upon the shoe; Fig. 5 is a front elevation of the machine, the jacks and pressing forms being removed; Fig. 95 6 is a detail plan view showing the clutch controlling shaft; Fig. 7 is a side elevation, Fig. 8 is a bottom plan view, and Fig. 9 is a vertical sectional view of the flexible carrier for the sole pressing pad; Fig. 10 100 is a side elevation, and Fig. 11 is a plan view of the sole pressing pad.

The preferred form of the invention is illustrated as embodied in a progressive pressure, sole-laying machine of the type 105 shown in the patent to Mayo above referred

to. In laying soles with this machine, a lasted shoe is supported upon the jack, a sole is placed above the shoe and held in position by a sole locating device, and then 5 the pressing form is brought down into contact with the sole, and pressure is progressively applied to the upper surface of the form.

Since the machine includes two separate 10 sets of jacks and coöperating pressing forms, as well as their actuating devices, which have a substantially identical construction, only a single set will be described in detail.

15 The shoe supporting jack, Figs. 1, 3 and 4, consists of a heel post 20, and a toe rest 22, which are adjustably mounted to move toward and away from one another upon a bedplate 24. The adjustment of the heel 20 post and toe rest for different sizes of lasts, is made by means of a hand screw 26 which is held in the bedplate and threaded through blocks secured to the bottom of the heel post and toe rest. To adapt the jack for 25 treating different styles and sizes of lasts, the bedplate 24 is mounted upon a screw 28 which passes into the machine frame. A nut is threaded on the screw and held in position upon the machine frame by means 30 of a pair of clips 30 which engage a flange 32 on the bottom of the nut. By this means, the jack may be vertically adjusted to any desired position.

When the lasted shoe is placed upon the 35 jack, the bottom face of the sole is up so that the operative cannot see the relation of the sole to the upper. For this reason a sole locating mechanism is employed to accurately position the sole upon the bottom of 40 the shoe. The sole locating mechanism, Figs. 1, 2, 3 and 4, consists of a series of gages 34 which surround the lasted shoe and have an upper engaging face and a sole locating face. The gages 34 are telescopically 45 mounted in carriers 36 which are rotatably mounted upon shafts 38 at the sides and back of the jack. The gage carriers are connected together by springs 40 which normally tend to hold the gages pressed against 50 the shoe upper. When placing a shoe upon the jack, the gages are spread away from the jack by means of a foot treadle 42 which is connected by means of a link 44 and lever 46 with the shaft 38 at the back of the jack. 55 The shafts 38 are all geared together, so that a single movement of the treadle will simultaneously spread all of the gages. The sole engaging faces of the gages are normally projected above the bottom of the shoe 60 by means of springs which are mounted in the carriers at the base of the gages. These gages projecting above the bottom of the sole, form a receptacle into which a sole may be readily inserted. In locating the sole, 65 the operative merely forces the sole against

the gage at the heel end of the shoe, and the springs connecting the gages tend to center it and properly locate it with reference to the shoe upper. When the pressing form is brought down to lay the sole, it first 70 engages the sole locating faces of the gages and forces them down across the edge of the sole, until the tops of the gages are flush with the surface of the sole. The gage faces always remain in contact with the sole and 75 tend to hold it in proper position.

The sole pressing form illustrated in the drawings is a pad for laying soles, and consists of a yieldable pad 48 which is attached to a flexible carrier 50. The front end of the 80 carrier is mounted in a pad-applying frame 52, and the rear end of the carrier is pivotally connected with an anchor post 54 which is mounted upon the jack bedplate 24. The pad 48 is a continuous single strip of material, usually rubber, and when not in pressure position on the sole, it is held suspended above the sole by the pad-applying frame. The pad-applying frame 52, Figs. 3, 4 and 5, consists of a pair of side arms 56 which are 85 tied together at their forward ends by a bar 58. The rear ends of the arms 56 are pivoted at one side to a side column 60 and at the other side to a central column 62 of the machine frame. The pad-applying 90 frame is positively oscillated toward and from the shoe in applying and removing the pad from a sole. The pivots of the pad-applying frame and pivot of the pad carrier on the anchor post 54 are substantially concentric, so that the carrier and frame swing together. 95

The pad carrier, Figs. 7, 8 and 9, consists of a series of metal sections 64 which have over-lapping lugs 66 that are pivoted together by means of headed pins 68. The lugs 66 and the flanges 71 are formed below the upper face of the section 64 to bring the axes of the pivot pins 68 approximately in line with the pressing face of the pad 48. 100 With this construction the bending of the carrier, when applying the pad to the sole of a shoe, is facilitated because the pivotal axis of the carrier sections approximately coincides with the upper face of the sole. 105 Further, the pressure which is placed on the sole is applied to the flanges 71 in order to apply the pressure as closely as possible to the line of the upper face of the sole. Each section is hollow and has a cushion flange 70 at its rear end and pressure flanges 71 at each side. In the hollow portion of the sections is cemented a cushion 72, usually leather or other yieldable material, which is held from longitudinal movement by the flanges 70. The sole-locating pad rests on the cushions 72 and is fastened to the end sections of the carrier by means of bolts 73 which pass through the pad and are threaded into the sections. The section at the for- 110 115 120 125 130

ward end of the carrier is mounted upon a rod 74 which is secured in blocks 76 that are slidably mounted in guides 78 formed in the side arms 56 of the pad-applying frame. 5 The rear section of the pad carrier is secured to a rod 80 which is mounted in a yoke 82 that is pinned to the upper end of a plunger 84 swiveled in the anchor post 54. The plunger 84 is yieldingly supported in 10 the post 54 upon a spring 86 which is pressed against an adjusting nut in the bottom of the post. The yielding mounting of the plunger 84 provides for the correct positioning of the pad upon the heel end of the 15 shoe, and allows the rear end of the carrier to yield when pressure is applied in laying the sole. The blocks 76 in the side arms of the pad-applying frame are arranged to yield against springs 88 which are mounted 20 between the ends of the blocks 76 and adjusting screws 90. This construction permits a relative movement of the pad and carrier so that the pad may be properly positioned upon the sole. The position of the 25 pad 48 longitudinally of the shoe may be varied by adjusting the post 54 on the bed-plate 24. The movable mounting of the forward end of the pad carrier also provides for the longitudinal adjustment of the 30 pad carrier.

The pad-applying frame is oscillated, in placing the pad upon a sole and withdrawing it from the sole, by the operation of a pressure cradle which is oscillated back and forth across the shoe to place a rolling pressure upon the pad carrier. The pressure cradle, Figs. 3 and 5, consists of a pair of sectors 92 formed on the hubs 94 which are pivoted on a shaft 96 fixed to the machine frame. The arc-shaped extremities of the sectors are secured together in a spaced relation by means of tie rods 98, and are arranged to move back and forth across the jack between the side arms 56 of the pad-applying frame. An arm 100 projects rearwardly from each of the sector hubs 94, and these arms are connected by means of a link 102 with a crank 104 on the main driving shaft 106. Upon the forward ends of the 50 sectors are mounted rolls 108 which project into cam grooves 110 formed on the inner side of the side arms 56 of the pad-applying frame. The cam grooves 110 have a sharp turn at their rear end so that in the 55 first portion of the forward movement of the pressure cradle, the rolls 108 will rotate the pad-applying frame about its axis and quickly place the pad simultaneously upon the entire surface of the sole. After the pad 60 is placed on the sole, the rolls 108 travel in the forward portions of the cam grooves 110, which have a shape substantially the same as that of the top of the last, and serve to draw the pad tightly down upon the sole 65 as the cradle moves across the shoe. In the return movement of the cradle, the form will remain upon the sole until the rollers 108 come to the rear ends of the cam grooves 110, when the pad-applying frame will be quickly lifted to carry the pad off of the sole. 70

When the pressure cradle is moved forward into active position, a progressive rolling pressure is applied to the outer edges of the pad carrier. To this end a series of pressing rolls are movably mounted in a 75 series of radial slots 112 formed in the arc-shaped extremities of the sectors 92. The pressing rolls consist of a plurality of pairs of circular disks 114, each pair of disks being formed upon a shaft 116. The ends of 80 each shaft 116 project outwardly beyond the disks 114, and are journaled in blocks 118 which are slidably mounted in the slots 112. The blocks are pressed toward the bottom of the slots by means of a series of 85 springs 120 which are mounted between the blocks 118 and adjusting screws 122. By an adjustment of the springs 120, the pressure of each roll can be varied independently of the other, to vary the pressure applied 90 at different portions of the sole. When the disks 114 travel across the carrier 50, they roll over the pressure flanges 71 formed on the carrier, and pressure is applied only at the edges of the carrier which are outside of 95 the edges of the sole. In this way, pressure is not applied directly to the sole but is imparted to the sole through the cushions 72 and pad 48.

The two sets of sole supporting jacks and 100 coöperating sole pressing forms have independent driving mechanisms, and are arranged to be independently connected with their driving mechanisms. The driving clutches and the devices for connecting the 105 clutches for driving the forms are substantially the same as those shown in the patent to Mayo, No. 861,746, granted July 30, 1907. These clutch-connecting devices have the usual clutch-controlling levers 124 110 which are mounted upon clutch-controlling shafts 126 journaled in the machine frame (Figs. 1, 5 and 6). To connect the clutch so that a form may be operated the controlling lever 124 is oscillated in a counterclockwise direction. When the lever 124 is oscillated a roll 128 mounted on its forward end is received from one of a pair of stopping notches 130 formed in a cam disk 131 which is secured upon the end of the main 115 driving shaft 106. The clutch-controlling lever is oscillated by means of a foot treadle 132 which is attached to a rod 134 (Figs. 1 and 5) extending from the front to the rear of the machine. The rod carries a cam 136 120 which works against a roll 138 on the outer end of the controlling lever 124. When the treadle 132 is pushed down, the cam 136 raises the roll 138, and moves the controlling lever 124 against the action of a spring 130.

140, to draw the roll 128 out of a notch 130 on the cam disk. At the same time the clutch is connected to turn the main shaft 106. After the main shaft has commenced 5 to rotate, the treadle 132 may be released, and the roll 128 on the controlling lever will rest upon the periphery of the cam disk 131 while the main shaft continues to rotate. It will be noted that the stopping notches 10 130 in the cam disk are diametrically opposed, so that the main driving shaft will only make one-half of a revolution, when the controlling lever will be automatically drawn into a notch 130 by the spring 140 to 15 disconnect the clutch and stop the form. While the main driving shaft is making one-half a revolution, the pressure cradle is moved from an inactive position to an active or pressure position, or is moved from 20 an active position to an inactive position.

The treadle actuated cams 136 for operating the controlling levers are interconnected by means of a link 142 so that when one of the treadles 132 is depressed to connect the 25 corresponding form with the driving mechanism, the opposite treadle is elevated above neutral position in the manner shown clearly in Mayo Patent No. 861,746 above referred to. In the present machine mechanism is 30 provided for returning both treadles to a neutral position as soon as the pressure upon one of the treadles is relieved. To this end a pair of spring pressed plungers 144 are mounted in brackets 146 attached to 35 the front of the machine frame immediately above the treadles 132. When one of the treadles has been elevated above neutral position owing to the depression of the opposite treadle the plunger tends to return 40 it to neutral position when the pressure upon the opposite treadle is released. This immediately returns the cams 136 to a neutral or inoperative position and permits the roll 128 to drop into one of the recesses 130 45 after the shaft 106 has made one-half a revolution. If the form is out of pressing position when the treadle is initially depressed the machine will stop with the form located in pressing position and in order to move 50 the form back out of pressing position it is necessary to again depress the treadle and start the machine. The manipulation of one treadle does not affect the operation of the other form so that each treadle independently 55 operates its respective form.

In order to cause the simultaneous operation of both forms at once the shaft 148 (see Fig. 6) is arranged to be locked from movement with the clutch controlling shafts 60 126. The shaft 148 is mounted concentrically with the shafts 126 between sleeves 150 which are pinned to the ends of the shafts 126. The sleeves 150 have a clutch slot 152 into which project teeth 154 on sleeves 156, 65 which are pinned on the shaft 148. The

length of the slot 152 is greater than the corresponding length of the teeth 154 so that the clutch controlling shafts 126 may be independently oscillated when the forms are connected with their respective driving mechanisms through the treadles 132. An oscillatory movement of the shaft 148, however, will serve to rotate both of the shafts 126 simultaneously and move both controlling levers 124 to connect the two forms with the driving mechanism. The shaft 148 is operated by means of a foot treadle 158 which is pinned to the shaft 148 and projects forwardly to the front of the machine. This treadle is normally held in elevated position by means of a spring 160 which is connected between the treadle and the machine frame and when the treadle is in elevated position the teeth 154 of the shaft 80 clutches are held in a position to allow the 85 clutch controlling levers 124 to be independently operated.

With this arrangement, when the treadle 158 is employed, both jacks are connected simultaneously to the driving mechanism 90 and are respectively moved into and out of pressing position; but if it is desired to operate one form independently of the other, the separate treadles 132 are employed. By using these separate treadles one shoe may 95 be subjected to repeated pressures under the action of the forms or remain for a longer period under pressure if so desired while a number of shoes are acted upon by the opposite form. 100

Although the invention has been described as embodied in a sole-laying machine, obviously it may be embodied in any type of sole-pressing machine, and except as defined by the claims the invention is not 105 limited to any specific type of sole pressing machine.

The invention having been thus described, what is claimed as new is:

1. A sole pressing machine having, in 110 combination, a continuous sole pressing form, a shoe supporting jack, means for securing a relative actuation of the jack and form to apply the form to the entire surface of the sole simultaneously, and 115 means to apply a pressure to the form which progresses from end to end of the form.

2. A sole pressing machine having, in combination, a continuous sole pressing form, a shoe supporting jack, means for securing a relative actuation of the jack and form to apply the form to the entire surface of the sole simultaneously, and means for applying a rolling pressure to the form. 120

3. A sole pressing machine having, in 125 combination, a shoe supporting jack, a continuous sole pressing pad, a flexible carrier for the pad, means for securing a relative actuation of the jack and carrier to apply the pad simultaneously to the entire surface 130

of the sole, and means to apply an additional pressure on the pad.

4. A sole pressing machine having, in combination, a shoe supporting jack, a continuous sole pressing pad, a flexible carrier for the pad anchored at one end to the machine frame, a pad applying frame supporting the other end of the carrier, means for actuating the pad applying frame to place 10 the pad upon and withdraw it from the sole of a shoe upon the jack, and means to apply pressure to the pad.

5. A sole pressing machine having, in combination, a shoe supporting jack, a continuous sole pressing form, means for securing a relative actuation of the jack and form to apply the form to the sole of a shoe, and means for applying pressure to the sides of the form beyond the marginal portion of the 20 sole.

6. A sole pressing machine having, in combination, a shoe supporting jack, a sole pressing form, means for securing a relative actuation of the form and jack to apply the 25 form to the surface of the sole, and means for applying a rolling pressure to the form below its upper face.

7. A sole pressing machine having, in combination, a shoe supporting jack, a sole 30 pressing form, means for securing a relative actuation of the jack and form to apply the form to the sole of a shoe, and means for applying a progressive pressure to the form below its upper face.

35 8. A sole pressing machine having, in combination, two sets of shoe supporting jacks and coöperating sole pressing forms, a driving mechanism for relatively actuating each form and jack, a source of power devices for connecting each driving mechanism separately with the source of power, and means for holding the connecting devices in a neutral inoperative position.

9. A sole pressing machine having, in 45 combination, two sets of shoe supporting jacks and coöperating sole pressing forms, a driving mechanism for relatively actuating each form and jack, a source of power, a device and an operating treadle thereof for separately connecting each driving mechanism with the source of power, and means for simultaneously connecting both driving mechanisms with the source of power.

10. A sole pressing machine having, in 55 combination, two sets of shoe supporting jacks and coöperating sole pressing forms, a driving mechanism for relatively actuating each form and jack, a source of power, devices for connecting each driving mechanism 60 separately with the source of power, means for simultaneously connecting both jacks and forms with the source of power, and means to normally hold said connecting devices in neutral inoperative position.

65 11. A sole pressing machine having, in

combination, two sets of shoe supporting jacks and coöperating sole pressing forms, a driving mechanism for relatively actuating each form and jack, a source of power, means for independently connecting each 70 driving mechanism with the source of power, a treadle and a controlling lever for each mechanism, each lever being mounted on an independent controlling shaft, and means for operating both of the shafts simultaneously to connect both driving mechanisms to the source of power.

12. A sole pressing machine having, in combination, two sets of shoe supporting jacks and coöperating sole pressing forms, a 80 driving mechanism for relatively actuating each form and jack, a source of power, treadle operated devices for independently connecting each driving mechanism with the source of power, connections between the 85 treadle operated devices, treadle operated mechanism for simultaneously connecting both driving mechanisms with the source of power, and means for holding said treadle operated devices in a neutral position. 90

13. A sole pressing machine having, in combination, a shoe supporting jack, a pad applying frame, a continuous sole pressing pad suspended between the machine frame and the pad applying frame, and means to 95 operate the pad applying frame to place the pad upon the sole of a shoe and apply pressure to the pad.

14. A sole pressing machine having, in combination, a shoe supporting jack, a pad 100 applying frame mounted to swing over the jack, a pressure cradle mounted to swing over the jack, a continuous pad mounted on a flexible carrier suspended from the pad applying frame, connections between the 105 cradle and pad applying frame, and means to operate the cradle to place the pad on the sole of a shoe and apply pressure to the pad.

15. The combination of a shoe supporting jack, a continuous sole pressing pad, a 110 flexible carrier formed in sections for supporting the pad, means for oscillating the carrier to move the pad into and out of contact with a sole supported on the jack, and means to apply pressure to the carrier to 115 press the sole.

16. The combination of a shoe supporting jack, a carrier built up of hollow sections, a cushion in each section, a continuous sole pressing pad attached to the carrier and resting on said cushions, means for moving the pad into and out of contact with a sole supported on the jack, and means to apply pressure to the carrier. 120

17. The combination of a shoe supporting jack, a carrier built up of hollow sections, a cushion in each section, a pad attached to the carrier and resting on said cushions, a pressing flange on each side of said sections, means to move the pad into and out of con- 125

tact with a sole supported on the jack, and a series of pressing rolls movable over the flanges of the carrier sections to apply pressure to the sole.

5 18. A sole pressing machine having, in combination, a machine frame, a shoe supporting jack, a continuous sole pressing

form, a form applying frame, a yielding connection between the form applying frame and the form, a pivotal connection between the form and the machine frame, and means to operate the form applying frame and apply pressure to the form.

EDWARD E. FOSTER.
